SHOE CONFORMING APPARATUS

Jacob S. Kamborian, West Newton, Charles J. Dyer, Watertown, and Alan G. Baker, Plymouth, Mass.; said Dyer and Baker assignors to Kamborian

Filed Aug. 17, 1960, Ser. No. 50,177
19 Claims. (Cl. 12—8.2)

This invention relates to shoe machines, and particularly to an apparatus for snugly conforming a shoe upper to the shape of the shoe last upon which the upper is mounted during relative heightwise movement between the shoe upper and the conformer.

In application Serial No. 34,564, filed June 7, 1960, there is disclosed a flexible shoe conformer comprising a deformable yoke having a bight and legs extending away from the bight on opposite sides of the bight. Resilient means are provided for yieldably urging the bight and the legs of the yoke inwardly of the yoke. The yoke mounting means include a plurality of elements pivotally connected for relative swinging movement about vertical axes.

An object of this invention is to provide an improved conformer having the same general function as the conformer disclosed in the aforementioned application. To carry out this object, a pair of leaf springs are provided that extend along the outside walls of the yoke legs from the bight of the yoke to a point remote from the bight. The legs of the yoke are connected to the frame by means of supports rigidly secured to the frame. The yoke legs are connected to the supports by means of screws pivotally mounted in the supports, rods slidably mounted in the screws and yieldably urged towards the yoke legs, and a pivotal connection between the rods and support arms that are connected to the yoke legs.

The invention also includes an improved connection between said support arms and the yoke legs comprising a limb connected to the support arm inserted in a slot in the yoke leg, this connection permitting relative motion between the yoke leg and support arm to take place.

A troublesome aspect in the use of the conformer in a toe lasting machine such as that illustrated in Patent No. 2,888,693 is the tendency of the resiliently urged yoke bight and yoke legs to close inwardly of the last should the last be lowered an amount sufficient to place the top of the insole below the bottom of the yoke. A further object of the invention is to overcome this difficulty. This is attained by placing a stop mechanism co-operating with the control linkage of the machine that will preclude the lowering of the shoe an amount sufficient to cause this undesired action to take place.

The invention will now be described in greater detail with reference to the accompanying drawing wherein:

FIG. 1 is a vertical view partly in section of a toe lasting machine showing the wipers, the shoe support and the shoe conformer;

FIG. 2 is a plan view of the front of the machine with the cover removed showing the wipers, the wiper driving mechanism and the shoe conformer;

FIG. 3 is a schematic view partly in section, showing part of the control mechanism for driving the wipers;

FIG. 4 is a plan view of the shoe conformer and the means for mounting the conformer in the machine;

FIG. 5 is a side elevation view of the conformer shown in FIG. 4;

FIG. 6 is a perspective view of the control handle and associated parts including the valve for effecting horizontal movement of the wipers;

FIG. 7 is a front elevation view of part of the conformer shown in FIG. 5;

2

FIG. 8 is a vertical section taken along the line 8—8 of FIG. 5;

FIG. 9 is a vertical section taken along the line 9—9 of FIG. 4; and

FIG. 10 is a vertical section showing the relationship of the last, upper, insole, yoke legs and wipers.

Referring to FIGS. 1 and 2, there are wipers 10 and 11 and a wiper carrying slide 12 arranged on a frame 14 to move in a horizontal path forwardly and rearwardly, 10 and a shoe support comprising a toe rest 16 and a heel pin 18 mounted on a carriage 20 for movement vertically to raise a shoe into a position to be operated on by the wipers. The shoe support may be made substantially in accordance with the support disclosed in Patent No. 2,668,967. The slide 12 is operably connected to a motor 22 and the carriage 20 is operably connected to a motor 24. In accordance with Patent No. 2,888,693, there are valves V¹ and V² for controlling the flow of fluid to the motors and a single control handle 26 movable forwardly 20 and rearwardly in a horizontal plane and rotatable about its longitudinal axis to respectively produce forward and rearward movement of the wipers and up and down movement of the support. The valve V¹ (FIG. 6) is fastened to the underside of a horizontal bracket plate 28 and the latter, in turn, is fastened to the underside of the slide 12 by a vertical bracket plate 30, so that the valve V¹ moves forwardly and rearwardly with the slide. The handle 26 is connected to the frame 14 by way of a pivoted arm 32 and the latter contains a slot 34 through 30 which projects a pin 36 fastened to a stem 38 at the end of the valve spool 40 of the valve V¹ (FIGS. 3 and 6).

The valves are of the balanced type disclosed in Patent No. 2,888,693, so that when force is removed the valve spools will return to their normal position.

35 The valve V² (FIG. 1) is movable with the carriage and rotation of the handle 26 about its axis operates through link means comprising a cam 42 and linkage 44 to displace the spool in the valve V², thereby to supply fluid pressure to one end or the other of the motor 24. 40 A spring 46 on the spool causes it to follow the linkage during counter clockwise rotation of the handle.

Reference is made to the aforementioned Patent No. 2,888,693 for a more detailed disclosure of the mechanism for moving the wipers and the shoe support in response to manipulation of the handle.

45 Forward and rearward movement of the slide 12 may produce movement of the wipers 10 and 11 towards and away from the shoe in a manner similar to that disclosed in Patent No. 2,668,967. The forward end of the slide 12 rests upon a wiper support 48 which may, for example, be a web integral with the cap 50 of the frame 14, and which extends across the cap from one side to the other. The wiper support 48 is provided with a smoothly finished upper surface forming a guide for a pair of wiper actuators 52 and 54, whose undersurfaces are shaped to provide guideways for the wipers 10 and 11. The forward end of the slide 12 has pivotally connected to it the rear ends of links 53 and 55 which extend forwardly beneath the wiper actuators and are pivotally connected thereto at their forward ends. The wiper actuators are provided with slots of proper shape to impart the desired wiping movement to the wipers and movement of the actuators is effected through the aforesaid links by reciprocation of the slide 12. Reference is made to the aforementioned Patent No. 2,668,967 for a more detailed disclosure of the mechanism for moving the wipers in response to the reciprocation of the slide 12.

70 The shoe comprises an upper 63 and an insole 64 mounted on a last 66 (see FIG. 10). The function of the wipers 10, 11 is to gather the upstanding lasting margin 68 of the upper 63 and wipe and fold it over the top of the

insole. The wiped lasting margin is secured to the insole by adhesive, tacks, staples, or any other appropriate means. It is desirable that, prior to the movement of the wiper across the insole, the upper snugly conform to the shape of the last so that, after the wiping operation, there will be no wrinkles or irregularities in the upper. It is for this purpose that the shoe conformer 57 forming the instant invention has been provided.

The conformer 57 comprises a yoke 58 made of flexible deformable material, preferably having a low coefficient of friction so as not to mar the upper. While other suitable material may be used, Teflon has been found to be the most satisfactory material out of which to fashion the yoke. The yoke is generally U-shaped and has a bight 60 positioned in the forward end of the frame 14 and a pair of legs 62 each of which extends forwardly of the bight.

A head 70 is slidably mounted in a guideway 71 formed in the wiper support 48. The wiper support has shoulders 72 extending on opposite sides of the guideway 71, and gibs 74, secured to the top of the wiper support 48, extending alongside the guideway 71 (see FIG. 8). The head 70 has tongues 76 adapted to slide in the grooves formed between the shoulders 72 and gibs 74. The head 70 has a socket 78 in its forward end adapted to receive the bight 60 of the yoke 58. A bracket 80, positioned rearwardly of the head 70, is secured to the gibs 74 by screws 82 and has a portion extending downwardly into the guideway 71. A stud 84 is threaded into the bracket 80. The stud 84 extends rearwardly and terminates short of the frame 14. An opening 86 (FIG. 1) is provided in the frame in alignment with the stud and the end of the stud has a kerf adapted to receive a screwdriver bit. A socket 88 is provided in the head 70 and a compression spring 90 extends from the socket 88 to a reduced portion 92 on the stud 84. The spring 90 serves to yieldably urge the head 70 forwardly along the guideway 71. A screw 94 threaded into a portion of the frame 14 is in abutting relation to the head 70 and thereby limits the extent the head may be moved along the guideway under the resilient force of the spring 90.

Supports 96 are rigidly secured to the opposite sides of the frame 14 at the forward end thereof and extend forwardly of the frame. An internally threaded sleeve 98 is pivotally connected to each support 96. Each sleeve has a cylindrical bearing 100 (FIG. 7) extending upwardly therefrom into an opening in its associated support 96. Integral with each bearing 100 and extending upwardly therefrom is a threaded rod 102 onto which is threaded a nut 104. The sleeves 98 are thereby pivotally mounted in the supports 96 so that they may swing about the vertical axes of the bearings 100.

A threaded shaft or screw 106 is threaded into each sleeve 98 and a knob 108 is rigidly connected to each screw 106. Each screw is hollow and slidably receives a rod 110 extending longitudinally therethrough. Adjusting nuts 112 are threaded to the outer ends of the rods 110 and bear against bearings 113 rotatably mounted on the rods 110. The bearings 113 in turn bear against the knobs 108. The inner end of each rod 110 is formed into a head 114 that extends between the jaws of a clevis 116. Each clevis 116 forms an end of a support arm 118. The heads 114 are pivotally connected to the clevises 116 by pins 120 so as to permit relative swinging movement between the rods 110 and the support arms 118 about the vertical axes of the pins 120. A compression spring 122 is mounted on each rod 110 and extends from each screw 106 to each head 114. The ends of the support arms 118 remote from the clevises 116 are pivotally connected to the head 70 by pins 124 so as to permit relative swinging movement between the support arms 118 and the head 70 about the vertical axes of pins 124. The pins 124 are received in lugs 126 in the head 70, the lugs extending on opposite sides of the socket 78 in the head.

The bight of the yoke 58 is normally positioned in abutting relation to the base of the socket 78. Extending

inwardly from each support arm 118 adjacent each clevis 116 is an L-shaped flange 130 (FIG. 9) having a horizontal limb 131 and a vertical limb 133. Each vertical limb is receivable in an elongate lengthwise extending slot 132 provided in each yoke leg 62, the vertical limbs being shorter than the slots. A hold-down finger 134 is pivoted to each support arm 118 in such a position that it may be swung over the associated vertical limb 133.

A leaf spring 136 having a bow 138 extends from the bight 60 of the yoke along the outside wall of each yoke leg 62 for a distance extending part way along the length of each yoke leg. A jacket 139 is mounted on the bight 60 of the yoke and envelops both springs 136. The bight of the yoke, the springs 136 and the jacket 139 are secured to each other by a pin (not shown) extending therethrough. The leaf springs 136 are thus mounted to apply resilient pressure inwardly of the yoke.

In the operation of the conformer, the screw 94 is adjusted to set the forwardmost position of the head 70, and the stud 84 is rotated in the bracket 80 to obtain the desired tension in the spring 90. The knobs 108 are rotated to thereby bring the screws 106 the desired distance from each other. Since the nuts 112 act as limit stops due to the springs 122 causing the nuts 112 to abut against the bearings 113, the heads 114 will always be maintained a constant distance from the inner ends 140 of the screws 106 regardless of the setting of the screws 106, and the axial movement of the screws 106 will move the clevises 116 of the support arms 118 toward or away from each other a corresponding amount. The rotation of the knobs 108 will therefore alter the profile of the inner walls 142 of the yoke 58 and alter the distance between the walls 142. This alteration will provide for a greater or lesser pressure of the yoke legs 58 against the upper, the desired amount of such pressure being dependent on the physical characteristics of the material out of which the upper is fashioned and the shape of the last. The alteration in profile of the walls 142 will also change the length of said walls bearing 40 against the shoe upper. The extent of this length desired is dependent on the amount of lasting margin to be folded over the insole by the wipers. By rotating the nuts 112, the distance between the clevises 116 and the screw ends 140 may be changed and the tension of the springs 122 may be adjusted.

The shoe mounted on a last is placed on the shoe support so that the upper 68 is positioned above the conformer in the position indicated in phantom in FIG. 4 with the toe end of the shoe facing the bight 60. At 50 this time the edges of the shoe will overlap the inwardly facing wall 142 of the yoke. The last is then forced downwardly until the top of the insole 64 is substantially in the same plane as the bottom of the wipers 10 and 11 (see FIG. 10). Initially, during the downward movement of the shoe, the wall 142 of the deformable yoke 58 will be compressed. When the wall can no longer be compressed, the bight 60 of the yoke will flex rearwardly of the machine against the pressure exerted by the spring 90, and the legs 62 of the yoke will flex outwardly against the pressure exerted by the springs 136. Should the shoe be substantially wider than the space between the legs 62, the support arms 118 will swing outwardly about pivot pins 124 and compress the springs 122 between the heads 114 and the screw ends 140. During the latter movement, there will be relative swinging movement between the heads 114 and the clevises 116 about the pins 120 and relative swinging movement between the screws 106 and the supports 96 about the bearings 100. The yieldable pressure exerted by the springs 90, 136 and 122, and the aforementioned swinging movements will cause the yoke 58 to snugly engage the shoe upper 68 and cause the shoe upper to snugly conform to the shape of the last during the downward movement of the last.

After the shoe and last have completed their down-

ward movement, the shoe upper will be yieldably clamped between the last and the conformer as indicated in FIG. 10. At this time the wipers will be moved horizontally to move, fold or wipe the upstanding lasting margin 68 of the upper 63 over the insole 64 and the last may be raised upwardly against the wipers during the latter's horizontal movement to apply bedding pressure of the last against the wipers. The wipers and the shoe support may be moved independently or concurrently by the manipulation of the handle 26 to effect the lasting of the shoe as described in the aforementioned Patent No. 2,888,693.

Should the shoe support be lowered an amount sufficient to bring the shoe insole 64 below the level of the yoke 58, the springs 90, 136 and 122 may force the yoke over the top of the insole. In this event, should the operator reraise the shoe through the application of fluid pressure through the motor 24, the yoke may be damaged. To prevent this, an adjustable stop 144 (FIG. 1) is provided in position to abut a horizontal bar 146 on a link 148 forming part of the linkage 44. When the cam 42 is rotated in a direction to lower the shoe support, the bar 146 will be moved downwardly. When the bar 146 contacts the stop 144, further downward movement of the bar and therefore of the shoe support will be precluded. The stop 144 takes the form of a screw threaded into the horizontal flange of a bracket 150. The bracket 150 is rigidly secured to a guide 152, the guide being provided for guiding the link 148 in its vertical movement. The stop 144 is adjusted to a position where it will be contacted by the bar 146 when the shoe has been lowered to the extent that the top of the insole 64 is slightly higher than the bottom of the yoke 58.

In placing the yoke 58 in the machine, the bight 66 of the yoke is placed against the base of the socket 78, the slots 132 are slipped over the limbs 133, and the fingers 134 are swung over the slots 132. By making the slots 132 longer than the limbs 133, the conformer may be placed on the limbs 133 if the shape of the conformer legs 62 is different from that disclosed. The conformer is preferably made from flat stock and bent to the desired shape. The shape imparted to the conformer legs will be dependent on the shape of the last with which the conformer is to cooperate. In addition, the elongate slots 132 may allow some degree of relative movement between the conformer legs 62 and the limbs 133 when the last is forced downwardly through the conformer and thus aid in causing the conformer to conform snugly to the shape of the last. The hold-down fingers 134 prevent the conformer legs 62 from rising upwardly of the limbs 133 when the last-mounted shoe is moved upwardly through the conformer after the wipers have been retracted.

It is within the purview of the invention to use the shoe conformer in other organizations than that disclosed. For example, instead of having the shoe move downwardly through the conformer, it would be within the scope of the invention to have the shoe conformer mounted for movement heightwise of the shoe. The shoe conformer could also be used in a box-toe trimming machine to conform the upper to the shape of the last prior to trimming the box toe, lining and outer leather at the toe end of the shoe.

It should be understood that the present disclosure is for the purpose of illustration only and that this invention includes all modifications and equivalents that fall within the scope of the appended claims.

Reference is made to copending application Serial No. 90,565, filed February 20, 1961, in the names of Jacob S. Kamborian and Heinz W. Stemmler, which discloses a different shoe conforming apparatus having the same general purpose as the shoe conforming apparatus of the instant invention.

We claim:

1. A lasting machine having wiping means mounted for forward and rearward movement; a shoe support, on which a last-mounted shoe comprising an upper and insole is placed, mounted for relative heightwise movement toward and away from the path of movement of the wiping means; and a shoe conformer positioned below the wiping means and alongside the path of movement of the shoe, said shoe conformer comprising: a deformable yoke having a bight; a leg on each side of the bight extending away from the bight; and leaf spring means extending along the outside wall of each leg from a point adjacent the bight to a point remote from the bight.
2. The lasting machine according to claim 1 wherein said leaf spring means comprises: a leaf spring positioned alongside the outside wall of each leg; means securing an end of each spring to the bight of the yoke; and an outwardly extending bow in each spring intermediate the ends thereof.
3. A flexible shoe conformer comprising a deformable yoke having a bight, a leg on each side of the bight extending away from the bight, a leaf spring positioned alongside the outside wall of each leg, means securing an end of each spring to the bight of the yoke, and an outwardly extending bow in each spring intermediate the ends thereof, whereby the end of each leaf spring remote from the bight is resiliently urged against its associated yoke leg.
4. A flexible shoe conformer comprising a frame, a deformable yoke having a bight and a leg on each side of the bight extending away from the bight adapted to be mounted in the frame, said yoke being adapted to receive a last-mounted shoe interiorly thereof, a support rigidly secured to the frame on each side of the yoke, a shaft pivotally connected to each support so that it may swing about an axis transverse to the plane in which the yoke lies, means mounting each shaft so that it may be moved axially towards or away from a leg of the yoke, means connecting each shaft to a yoke leg so that axial movement of the shaft will move the yoke leg a corresponding amount, and means on the frame for receiving the bight of the yoke.
5. The conformer according to claim 4 having means for resiliently urging the bight of the yoke inwardly of the yoke.
6. A flexible shoe conformer comprising a frame, a deformable yoke having a bight and a leg on each side of the bight extending away from the bight, said yoke being adapted to receive a last-mounted shoe upper interiorly thereof, resilient means for urging the bight of the yoke inwardly of the yoke, means connecting each yoke leg to the frame, and spring means mounted to extend along the outside wall of each yoke leg and apply resilient pressure inwardly of the yoke, whereby during relative heightwise movement between the upper and yoke, the yoke will yieldably engage the shoe upper and cause the upper to snugly conform to the shape of the last.
7. A flexible shoe conformer comprising a frame, a deformable yoke having a bight and a leg on each side of the bight extending away from the bight, said yoke being adapted to receive a last-mounted shoe upper interiorly thereof, a head in engagement with the bight of the yoke, said head being slidably mounted in the frame, spring means for resiliently urging the head in a direction extending inwardly of the yoke, a leaf spring for urging the yoke legs inwardly extending along the outside wall of each yoke leg, means connecting each leaf spring to the yoke bight so that it will apply resilient pressure to the associated yoke leg in a direction extending inwardly of the yoke, and means connecting each yoke leg to the frame, whereby during relative heightwise movement between the upper and the yoke, the yoke will yieldably engage the upper and cause the upper to snugly conform to the shape of the last.
8. A flexible shoe conformer comprising a frame, a

deformable yoke having a bight and a leg on each side of the bight extending away from the bight, said yoke being adapted to receive a last-mounted shoe upper interiorly thereof, a head slidably mounted in the frame, said head having a socket facing the yoke in which the bight of the yoke is received, a spring engaging the end of the head remote from the socket for yieldably urging the head towards the bight of the yoke, spring means in engagement with the outside wall of each yoke leg for urging the yoke legs inwardly of the yoke, and means connecting each yoke leg to the frame at a point remote from the bight, said last named means including spring means for yieldably urging the associated yoke leg inwardly of the bight, whereby during relative heightwise movement between the upper and the yoke, the yoke will yieldably engage the upper and cause the upper to snugly conform to the shape of the last.

9. A flexible shoe conformer comprising a frame, a deformable yoke having a bight and a leg on each side of the bight extending away from the bight, said yoke being adapted to receive a last-mounted shoe upper interiorly thereof, means mounted in the frame for yieldably urging the bight of the yoke inwardly of the yoke, a support rigidly secured to the frame on each side of the yoke, a shaft pivotally connected to each support for swinging movement about an axis transverse to the plane of the yoke, means mounting each shaft so that it may be moved axially towards or away from the yoke, a support arm connected to each yoke leg at a point remote from the bight, and resilient means interposed between each shaft and each support arm for resiliently urging the yoke legs inwardly of the yoke, whereby during relative heightwise movement between the upper and the yoke, the yoke will yieldably engage the upper and cause the upper to snugly conform to the shape of the last.

10. A flexible shoe conformer comprising a frame, a deformable yoke having a bight and a leg on each side of the bight extending away from the bight, said yoke being adapted to receive a last-mounted shoe upper interiorly thereof, a head slidably mounted in the frame, said head having a socket facing the yoke in which the bight of the yoke is received, a bracket positioned in the frame on the side of the head remote from the yoke, spring means interposed between the head and the bracket for yieldably urging the head towards the bight of the yoke, stop means for limiting the extent the head may be moved under the influence of the spring means, a spring along the outside wall of each yoke leg for yieldably urging the leg inwardly of the yoke, each of said springs being secured at one end to the bight of the yoke, a support rigidly secured to the frame on each side of the yoke, an internally threaded sleeve pivotally connected to each support for swinging movement about an axis transverse to the plane of the yoke, a hollow screw threaded into each sleeve, a rod slidably mounted in the hollow of each screw, said rods being of greater length than the screws, a support arm pivotally connected to the head on each side of said socket for swinging movement about an axis transverse to the plane of the yoke, a head on the end of each of the said rods that faces the yoke, a pivotal connection between each of the said heads and the support arms permitting relative swinging movement between the heads and rods about axes transverse to the plane of the yoke, spring means interposed between each rod and each head for yieldably urging the associated head toward the yoke, stop means on each rod for limiting the extent each rod may be moved towards the yoke under the influence of its associated spring, and means connecting each support arm to a leg of the yoke at a point remote from the bight of the yoke, whereby during relative heightwise movement between the upper and the yoke, the yoke will yieldably engage the upper and cause the upper to snugly conform to the shape of the yoke.

11. A flexible shoe conformer comprising a frame, a deformable yoke having a bight and a leg on each side

of the bight extending away from the bight, said yoke being adapted to receive a last-mounted shoe upper interiorly thereof, means mounting the bight of the yoke in the frame, and means connecting each leg of the yoke to the frame, said last named means comprising an elongate slot in each yoke leg and a limb positioned within the slot having a shorter length than the slot, said limb being connected to said frame.

12. The apparatus defined in claim 11 including a hold-down finger mounted on each support arm and overlying the associated limb to restrain upward movement of the yoke leg relative to the slot.

13. The apparatus defined in claim 12 including means for movably mounting the hold-down finger so that it may be moved away from the associated yoke leg and limb to permit the removal of the yoke.

14. A flexible shoe conformer comprising a frame, a deformable yoke having a bight and a leg on each side of the bight extending away from the bight, each of said legs having an elongate slot therein, said yoke being adapted to receive a last-mounted shoe upper interiorly thereof, means mounting the bight of the yoke in the frame, means connecting the legs of the yoke to the frame, said last named means comprising a support arm associated with each yoke leg, each support arm being connected to the frame and extending alongside the outside wall of each yoke leg, and a limb connected to each support arm and positioned within each slot, each of said limbs being shorter than the associated slot.

15. A shoe lasting machine for in-wiping the upstanding lasting margin of a shoe upper over a shoe insole, said machine comprising a frame, shoe working means comprising a horizontally movable shoe wiper means and a shoe support on which a last-mounted shoe comprising an upper and an insole is placed, said shoe support being relatively movable heightwise with respect to the wiper means, a shoe conformer positioned beneath the wiper means and alongside the path of relative movement between the wiper means and the shoe support, said conformer comprising a deformable yoke having a bight and a leg on each side of the bight extending away from the bight, said yoke being adapted to receive the shoe interiorly thereof, means for mounting the yoke in the frame comprising resilient means for yieldably urging a portion of the yoke inwardly of the yoke, means for moving the wiper means horizontally over the shoe insole, means for effecting the said relative heightwise movement between the said two shoe working means, the last named means comprising a powered drive means connected to one of the shoe working means, a control member movably mounted in the frame, link means interconnecting the control member and the powered drive means whereby movement of the control member will cause the powered means to move the shoe working means connected thereto a corresponding amount, and stop means cooperating with said link means to preclude movement of the control member an amount that would cause the top of the insole to be positioned below the bottom of the yoke.

16. A shoe lasting machine for in-wiping the upstanding lasting margin of a shoe upper over a shoe insole, said machine comprising a frame, a horizontally movable shoe wiper means, a shoe support on which a last mounted shoe comprising an upper and an insole is placed, said shoe support being movable towards and away from the path of movement of the wiper means, a shoe conformer positioned beneath the wiper means and alongside the path of movement of the shoe, said conformer comprising a deformable yoke having a bight and a leg on each side of the bight extending away from the bight, said yoke being adapted to receive the shoe interiorly thereof, means for mounting the yoke in the frame comprising resilient means for yieldably urging at least a portion of the yoke inwardly of the yoke, powered means operatively connected to the wiper means for moving the wiper means horizontally over the shoe

insole, powered means operatively connected to the shoe support for moving the shoe support heightwise towards and away from the wiper means, a control member for controlling both said powered means, said control member being mounted in the frame for horizontal movement and for rotational movement independently or concurrently, means interconnecting the control member and said first named powered means responsive to horizontal movement of the control member to effect horizontal movement of the wiper means, link means interconnecting the control member and the second named powered means responsive to rotational movement of the control member to effect heightwise movement of the shoe support, and stop means positioned to abut said link means during the movement thereof in response to rotation of the control member to preclude rotation of the control member an amount sufficient to cause the top of the insole to be positioned below the bottom of the yoke.

17. A flexible shoe conformer comprising a frame, a deformable yoke having a bight and a leg on each side of the bight extending away from the bight, said yoke being adapted to receive a last-mounted shoe upper interiorly thereof, means mounting the bight of the yoke in the frame, and means connecting each yoke leg to the frame, the last named means comprising means permitting relative movement lengthwise of the yoke legs between each yoke leg and the frame part to which it is connected.

18. A flexible shoe conformer comprising a frame, a deformable yoke having a bight and a leg on each side of the bight extending away from the bight, said yoke being adapted to receive a last-mounted shoe upper interiorly thereof, means mounted in the frame for resiliently urging the bight of the yoke inwardly of the yoke, spring means mounted to extend along the outside wall of each yoke leg and apply resilient pressure inwardly of the yoke and means connecting each yoke leg to the frame, the last named means comprising means permitting relative movement lengthwise of the yoke legs be-

tween each yoke leg and the frame part to which it is connected.

19. A toe lasting machine for in-wiping the upstanding lasting margin of a shoe upper over a shoe insole, said machine comprising a frame, a horizontally movable shoe wiper means, a shoe support on which a last-mounted shoe comprising an upper and an insole is placed, said shoe support being movable towards and away from the path of movement of the wiper means, a shoe conformer positioned beneath the wiper means and alongside the path of movement of the shoe, said conformer comprising a deformable yoke having a bight and a leg on each side of the bight extending away from the bight, said yoke being adapted to receive the shoe interiorly thereof, means mounted in the frame for resiliently urging the bight of the yoke inwardly of the yoke, spring means mounted to extend along the outside wall of each yoke leg and apply resilient pressure inwardly of the yoke, means connecting each yoke leg to the frame, means for moving the wiper means horizontally over the shoe insole, means for moving the shoe support heightwise towards and away from the wiper means, the last named means comprising powered drive means connected to the shoe support, a control member movably mounted in the frame, link means interconnecting the control member and the powered drive means whereby movement of the control member will cause the powered means to move the shoe support a corresponding amount, and stop means cooperating with said link means to preclude movement of the control member an amount sufficient to cause the top of the insole to be positioned below the bottom of the yoke.
